UNITED STATES PATENT OFFICE.

CHARLES J. PEMBROKE, OF ROCHESTER, NEW YORK.

CARBURETER.

1,143,779.

Specification of Letters Patent. Patented June 22, 1915.

Application filed March 12, 1913. Serial No. 753,713.

To all whom it may concern:

Be it known that I, CHARLES J. PEMBROKE, of the city of Rochester, in the county of Monroe, State of New York, have invented certain new and useful Improvements in Carbureters; and I do hereby declare the following to be a full, clear, and exact description of the same, reference being had to the accompanying drawings, forming a part 10 of this specification, and to the reference-numerals marked thereon.

My present invention has for its object to provide a carbureter for vaporizing volatile fluids such as employed for forming the 15 explosive mixtures used in gas or explosive engines, in which the fluid discharged into the air intake passage or vaporizing chamber is regulated or controlled in proportion 20 to the volume of air coursing through said passage, in accordance with the speed of operation of the engine or the load under which the latter is operated.

To these and other ends the invention consists in certain improvements and combinations of parts, all as will be hereinafter more 25 fully described, the novel features being pointed out in the claims at the end of the specification.

In the drawings: Figure 1 is a vertical 30 sectional view of a carbureter constructed in accordance with one embodiment of my present invention; Fig. 2 is a similar view taken on the line 2^x—2^x of Fig. 1; Fig. 3 is a horizontal sectional view taken on the line 3^x—3^x of Fig. 1; Figs. 4 and 5 are sectional views similar to Fig. 2 showing the gates in the intake passage in the open and closed positions respectively; Fig. 6 is a transverse sectional view looking downward, the parts being shown in Fig. 4, and Fig. 7 is a vertical sectional view on the line 7^x—7^x of Fig. 5, showing the atomizing discharge end of the fuel outlet.

Similar reference numerals throughout 45 the several figures indicate the same parts.

In illustrating the carbureter which embodies a preferred form of my invention, I have shown the air intake passage or channel formed by a casing, which is preferably 50 rectangular in cross section, and into which the liquid fuel is discharged from a suitable nozzle fed from the main body of liquid. The body of liquid is preferably contained 55 in the float chamber A supplied through the pipe 1, the level of which is governed by the float 2, operating the needle valve 3.

The fuel discharge nozzle extends upwardly from the end of the laterally extending conduit 4 leading from the float chamber, said nozzle being preferably located centrally of 60 the air intake passage. The nozzle proper comprises a stand-pipe 5 which forms a continuation of the conduit 4.

In order to obtain a preliminary adjustment of the fuel supply, I provide means 65 for changing the relative portions of the nozzle and the coöperating valve to be described hereinafter, and while I may accomplish this by an adjustment of either element, or both, I prefer to obtain this result 70 by an adjustable tubular member 6, preferably threaded into the upper end of the stand-pipe 5, and movable longitudinally therein when rotated on the screw threads, this adjustment being easily accomplished 75 by the stem or rod 7, attached to the member 6 and extending outwardly through the gland or stuffing box 8. Other means than the screw threads mentioned might be employed for adjusting the member 6, or these 80 screw threads might be located at some other position, but I deem it preferable to arrange them as shown, because they perform the further function of closing the space between the contiguous walls of the stand-pipe 85 and tubular member and thus preventing the suction action in the carbureter from drawing the volatile oil through this space and requiring all of it to escape through the tubular member.

In the drawings this member is shown in the form of an enlarged head at the upper or inner end of the rod 7, which has an opening, indicated at 6^a, the lower end of said opening extending laterally and affording communication with the space within the standpipe 5. The fluid which escapes through the passage 6^a, instead of flowing in a single stream, is broken up or subdivided so that it escapes into the air intake 100 passage in a plurality of jets, which serve greatly to carry out the important function of thoroughly mixing the vapor from the volatile oil with the inrushing air. In carrying out this feature of the invention, I 105 surround the stand-pipe 5 with a spray head 8, having a vertical passage 8^a into which the liquid is received from the nozzle 6, and a horizontal passage 8^b, which extends transversely of the air intake passage, 110 and is provided with a plurality of laterally arranged openings or discharge apertures in

its opposite walls, as indicated by 8^c, of which fourteen are shown in the present illustration, although this number may be increased or decreased, if desired. By this arrangement, the liquid is discharged at right angles to the path of the inrushing air, causing a more thorough breaking up and vaporization of the fuel which is discharged in lateral sheets, as will appear presently. Of the several apertures, attention is called to those indicated by 8^d arranged midway in the passage 8^a, in alignment with and above the nozzle 6, as these supply the vapor required when the engine is operating at the lowest or cranking speed, at which times the remaining apertures 8^c are cut off by the air operated gates to be mentioned presently.

The outflow of liquid from the passage 6^a is controlled by a tapered needle valve 6^b fixed in the passage 8^a and coöperating with the perforation 6^a, the extent of the opening between the latter and the valve being determined in the present embodiment by the longitudinal adjustment of the head 6 in the stand-pipe 5.

The air intake passage is preferably rectangular in cross section, as shown in Figs. 3 and 6 and is composed of front and back plates 9 and 10 and the two side plates 11, which parts are connected by bolts 12, passing through ears 13, arranged preferably on the exterior of the parts providing a free and unobstructed interior. Surmounting the rectangular casing is a tubular section 14, containing the pivoted throttle valve 15, which can be opened and closed by oscillation of the lever 16 arranged exteriorly of the casing, which latter is adapted to be connected to the intake manifold of the gas engine, a portion of which is shown and indicated by 17.

A further important feature of my invention consists in providing means for increasing or decreasing the flow of gasolene or other volatile fluid fed to the carburetor in proportion to the volume of air demanded by the engine according to the working load imposed thereon. To this end I make the spray head movable for the purpose of adjusting the needle valve and I provide an air gate or gates which are operated by the pressure of the inrushing air in the intake passage to move the spray head or member 8 and the latter I preferably construct in the form of a weight, which will normally descend to its lowermost position and serve as means for closing the air gates when the pressure is reduced. The air gates are also so arranged and constructed that they will serve when in closed position to direct all of the air required at the lowest or cranking speed past the point of discharge of the apertures 8^d and when partially opened will direct the inrushing air currents across all of

the discharge orifices 8^c. While I prefer to employ gravity controlled gates, more or less satisfactory results are obtained by providing springs for moving the gates to closed position, in which event the spray head need not be weighted.

More specifically describing the structural features of the elements just referred to, attention is called to the fact that the spray head 8 is a solid rectangular metallic block 75 in which the vertical passage 8^a opens at its lower end and affords a sliding engagement with the stand-pipe 5, which may also serve as a guide, although I prefer to guide the block in the ways 9^a, 10^a in the walls 9 and 10. The air operated gates are indicated at 18 and 19 and are pivoted at their lower ends to the bottom edges of the side walls 11-11 and when in their normal position, they occupy the relatively inclined positions 85 shown in Figs. 2 and 5. The best results I have found are obtained when the gates are at an angle of approximately twenty degrees to the perpendicular when closed, although this may vary. The upper end of the spray 90 head 8 at the point where the discharge apertures 8^c open, is provided with two inclined surfaces, as shown at each side of the central cylindrical portion 8^e, which is provided to accommodate the central 95 recess 8^a and the valve head therein. The upper ends of the air gates overlie these inclined surfaces and rest against the lower portions of their faces when in the closed position, but the gates themselves are tapered at their upper extremities so while their upper edges project somewhat beyond the vapor discharge orifices 8^c, these are not actually closed, although by reason of the gates resting against the spray head, the 105 passage of air in sufficient quantities to exert a suction action on said orifices is obviated, but when the gates are ajar, a passage is provided between their under surfaces and the contiguous inclined surface of 110 the spray head, and sheets of air are directed across the open ends of the discharge orifices 8^c. Each of the gates is provided centrally with a recess 18^a and 19^a respectively, 115 which accommodate the boss 8^e, said recesses being of such dimension that when the gates are closed, a sufficient quantity of air is admitted for driving the engine at low speed and at such time directing all of the air, 120 which is drawn through the intake passage across the two central outlet orifices 8^d. The air gates and the combined spray head and weight 8 are fitted rather loosely in the casing forming the air inlet, so that they may operate with perfect freedom and in 125 order, therefore, to prevent unnecessary leakage of air when the gates are closed, diagonally inclined strips 18^b and 19^b are arranged on the front and rear walls 9 and 10, and it is also for the purpose of minimizing 130

the leakage of air that the spray head and weight 8 is guided at its two edges in recesses formed in the walls 9 and 10.

Simultaneous movement of the two air gates 18 and 19 as well as vertical adjustment of the needle valve, is accomplished by providing the gates with short operating fingers 18^a—19^a, the free ends of which are embraced between similar pairs of laterally projecting lugs 20 on each side of the member 8 near the bottom thereof, these parts being proportioned and designed that any air pressure in the intake passage will cause both gates to be moved equal distances and the spray head to be actuated so that the needle valve 6^b carried thereon will always occupy a definite predetermined relation to its coöperating valve seat, which is in direct proportion to the movement of the gate.

The bottom of the air intake passage may be open directly to the atmosphere, or if desired, a hood 21 may be fitted thereto, having at one side an air intake aperture 22 and provided with a laterally extending portion 23 forming a passage through which heated air may be introduced which is collected from some suitable point adjacent to the cylinder of the engine as will be understood.

As a means of improving the effective operation of the carbureter and assuring a thorough mixture of the inrushing air and vapor under certain conditions, as for instance when the operator suddenly opens the throttle from a partly closed position to a full open position, I provide above or below the throttle valve, as illustrated in Fig. 2, a perforated bell shaped baffle plate 24. This member is supported at opposite sides by two short legs 25, so that its edge 26 is for the most part free and clear of the surrounding casing or wall of the intake passage. At its center the baffle member is provided with the aperture 27, the area of which is sufficient to permit the free passage of such carbureted mixture as is required at low or cranking speed, but by reason of the shape of the bell, air in excess of this quantity impinging against its lower surface, will be deflected downwardly and required to circulate around the edge 26 of said member. In so doing, this portion of the air is brought into juxtaposition with the flat inflowing air sheets. This means of redirecting a portion of the first quantity of air admitted after the throttle is thrown wide open, is important, because previous to that instant, the engine is running at a low speed on a carbureted mixture of air passing through the ports 18^a and 19^a and vapor issuing from the two ports 8^a. Consequently the initial air passing the spray head the first instant the throttle is open, must be more rarefied than that which follows, after suction has been produced on the

other outlet orifices 8^a. Therefore, the turning back of a portion of the air first admitted, when the throttle is thrown wide open insures, in a multi-cylinder engine, that all of the cylinders will under these conditions obtain an explosive mixture of equal density.

In the present carbureter, I have provided means for controlling the flow of gasoline, or other volatile fluid employed, in proportion to the quantity of air demanded by the engine under various working conditions and the construction of the air gates, and their connection with the movable weighted head, is such as to cause them to normally exert a tendency to move to a closed position, and for this reason the parts are very sensitive and responsive to slight fluctuations of the air pressure in the intake passage. Consequently slight movements of the throttle valve will cause the speed of the engine to be increased or decreased almost instantaneously, and when the engine speed is cut down to the lowest point, flooding of the carbureter and consequent stopping of the engine by producing too rich a mixture will not occur.

I claim as my invention:

1. A carbureter including an air inlet and fuel discharge nozzle arranged in the air inlet, a fuel spray head extending substantially across the air inlet and provided with a plurality of laterally arranged apertures in its opposite walls, a valve carried by the spray head and a swinging gate disposed in the air inlet and operated by the inrush of air and adapted when opened to lie substantially parallel to the axis of the inlet and when closed to lie at an angle to the same, and connections between the valve and the gate.

2. A carbureter including an air inlet, a fuel discharge nozzle arranged in the air inlet, a movable fuel spray head extending substantially across the air inlet and surrounding the nozzle, the discharge head being provided with a plurality of transversely disposed apertures in its opposite walls, a valve normally fixed with relation to the head and coöperating with the nozzle, a swinging gate arranged in the air inlet, and connections between the valve and the gate.

3. A carbureter including an air inlet, a fuel discharge nozzle arranged in the air inlet, a spray head surrounding and movable on the nozzle, said spray head extending substantially across the air inlet and provided with a plurality of laterally arranged apertures in its opposite walls, a valve carried by the spray head, a swinging gate disposed in the air inlet, said gate being operated by the inrush of air and adapted, when open, to lie substantially parallel to the axis of the inlet and when closed to lie at an

angle to the same, and connections between the valve and the gate.

4. A carbureter including an air inlet, a nozzle disposed in the air inlet, a weighted spray head slideable longitudinally of the nozzle, a valve arranged in the spray head and coöperating with the nozzle, said head being provided with a plurality of laterally disposed apertures in its opposite walls, a

plurality of swinging gates pivoted at the 10 sides of the inlet and adapted to contact with the spray head when closed, and connections between the gates and the head.

CHARLES J. PEMBROKE.
